UNITED STATES PATENT OFFICE.

EMIL DEISTER, OF FORT WAYNE, INDIANA, ASSIGNOR TO THE DEISTER CONCENTRATOR COMPANY, A CORPORATION OF INDIANA.

FEEDING DEVICE FOR ORE-CONCENTRATORS.

No. 895,075.

Specification of Letters Patent.

Patented Aug. 4, 1908.

Application filed October 15, 1906. Serial No. 338,953.

To all whom it may concern:

Be it known that I, EMIL DEISTER, a citizen of the United States of America, and resident of Fort Wayne, in the county of Allen 5 and State of Indiana, have invented certain new and useful Improvements in Feeding Devices for Ore-Concentrators, of which the following is a specification.

This invention relates to improvements in feed devices for ore concentrators, and the object thereof is to provide compensating means for irregularity of feed and to relieve the table of surplus water.

The above object is accomplished by the 15 construction illustrated in the accompanying drawings in which

Figure 1 is a plan view of the invention shown in connection with a concentrating table; Fig. 2 is an enlarged transverse section 20 of the same on the line $x-x$ of Fig. 1; and Fig. 3 is an enlarged longitudinal section on the line $y-y$ of Fig. 1.

Similar numerals of reference indicate corresponding parts throughout the several 25 views, and referring now to the same: 1 is a concentrating table, 2 is the head-board along the feed side of the table, and 3 is the projecting breast-board at the rear end thereof.

30 The invention consists of the feed box 4 which is divided partway of its length by a partition 5, thus affording a feed chamber 6 for the reception of pulp, and a settling chamber 7 into which passes surplus pulp from the former chamber.

A waste launder 8 leads from the rear end 45 of the settling chamber, and a wedge shaped block forms a dam 9 at its juncture with the launder. Another wedge shaped block forms a shoal 10 at the forward end of the box and prevents the pulp from splashing.

In the feed chamber 6 is a projecting metal plate 11 adjacent the side nearest the head-board 2, and feed openings 12 are made 50 therein which register with larger corresponding openings 13, the latter extending through the bottom of the box 4. Another feed opening 15 is made in the bottom of the box adjacent the shoal 10 in line with the former feed openings. An angle plate 16 extends along the bottom of the box and projects a short distance below the openings 55 therein and serves to spread the material as it is discharged therethrough.

55 A riffle 17 extends from the forward end of

the partition 5, in a slanting direction toward the row of feed openings and serves to divert the pulp in the feed chamber toward said openings 12, and allow the settled mineral to pass to the opening 15.

In the operation of this invention the table, together with the box, is reciprocated in the direction indicated by the arrow, and pulp is fed into the feed chamber at the rear end thereof. The pulp is discharged from the box through the feed openings, that portion lying above the plate 11 passes out through the openings 12 and the settled matter passes onward to the opening 15 and is discharged therethrough. In this manner most of the mineral is fed to the table at a point thereon nearer the forward or concentrates discharge end 18 while most of the gangue is fed to the table at points thereon nearer its rear end which is farthest from the concentrates discharge end.

Another feature in the operation of this invention is that, in case of a sudden rush of pulp, the overlying portion thereof overflows the riffle 17 and enters the settling chamber 7 50 wherein the mineral gravitates to the bottom and because of the differential action of the table is moved to the opening 15 and is discharged. Should the pulp rise in the settling chamber above the level of the dam 9, the surplus water, after being relieved of its contained mineral, overflows into the waste launder and is discharged thereby without passing onto the table. This is highly beneficial since the sudden rushes of water upon 90 the table disturbs the strata of ore matter thereon which is detrimental to concentration.

Having described my invention what I claim as new and desire to secure by Letters 95 Patent is:

1. In apparatus of the class described, a reciprocating table; a feed box in connection with the table, having a feed chamber and settling chamber which have communication 100 at the forward end of the former, the feed chamber having discharge openings which extend through the bottom of the box, and the settling chamber having a shoal at its forward end and a dam at its rear end, and having also a discharge opening at its forward end adjacent the shoal, and a waste launder having communication with the settling chamber at its rear end adapted to receive the overflow therefrom which passes over the 110

adjacent dam, and being adapted also to convey the same away from the table.

2. In apparatus of the class described, a reciprocating table; a feed box in connection with the table, which is divided part-way of its length by a partition, one part for a feed chamber and the other for a settling chamber, the feed chamber having a series of feed openings in its bottom, and the settling chamber having a feed opening at its forward end and a dam at its rear end; and a waste launder communicating with the settling chamber at its rear end adapted to receive the overflow which passes therefrom over the dam, and convey the waste away from the table.

3. In apparatus of the class described, a reciprocating table; a feed box secured to the table and having a feed chamber and settling chamber, the former communicating with the latter; an upwardly projecting plate in the feed chamber, having feed openings therein which extend through the bottom of the box, the settling chamber having a discharge opening in its bottom near its forward end; a riffle adapted to direct under-

lying mineral in the feed chamber toward said openings; and a waste launder communicating with the settling chamber at a point above the level of its bottom, and being adapted to convey overflow water from said box away from the table.

4. In apparatus of the class described, a reciprocating table; a feed box secured to the table, having a feed chamber and settling chamber which communicate with one another, and having also discharge openings leading from the feed chamber and another discharge opening near the forward end of the settling chamber; an upwardly projecting plate in the feed chamber, having openings therein which communicate with the openings which lead from the settling chamber; and an overflow outlet adapted to discharge waste from the settling chamber away from the table.

In testimony whereof I affix my signature, in presence of two witnesses.

EMIL DEISTER
